UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

WATER CRANE.

Application filed September 18, 1920. Serial No. 411,132.

To all whom it may concern:

Be it known that I, BARTON S. SNOW, a citizen of the United States, residing at Batavia, in the county of Kane and State of Illinois, have invented a new and useful Improvement in Water Cranes, of which the following is a specification.

My invention relates more particularly to water-crane located alongside railway tracks for the purpose of supplying the tenders of locomotives, with water; and my primary object is to provide a novel, simple and relatively economical construction of crane which shall be adapted for the supplying of tenders of different heights, throughout the wide range now presented in locomotive practice, and which shall require the raising of the water, for discharge, to a lower height than in the case of structures as hitherto provided.

Referring to the accompanying drawings:

Figure 1 is a view in elevation of a construction of water-crane constituting one of the embodiments of my invention, the well or pit in which certain operating parts of the crane are located, being shown in section. Figure 2 is a view in elevation viewing the structure from the right hand side in Fig. 1, the lower portion thereof being broken away, the spout portion in this view being shown by full lines in the position it assumes when normally positioned, namely, out of use, and by dotted lines in positions to which it may be swung for filling tenders on tracks between which the crane is interposed.

Figure 3 is an enlarged view similar to Fig. 1 of the upper end of the crane, showing certain parts in section and illustrating the spout section of the crane by full lines in uppermost position, and by dotted lines in depressed condition. Figure 4 is a plan view of the structure of Fig. 3 with the spout section and certain other parts omitted. Figure 5 is a view like Fig. 1, with the lower portion of the structure broken away, of another construction in which my invention is embodied. Figure 6 is a section taken at the line 6—6 on Fig. 5 and viewed in the direction of the arrows. Figure 7 is a view like Fig. 4, of still another construction embodying my invention, the lower portion thereof being broken

away. Figure 8 is a view in elevation, 55 partly sectional, of a part of the lower portion of the crane of Fig. 7; and Figure 9, a view in end elevation of the structure shown in Fig. 7, viewing the structure from the left hand side of the last-referred- 60 to figure.

Referring particularly to Figs. 1, 2, 3 and 4, the base or supporting member of the crane is represented at 10, this base being hollow and provided with an upwardly-extending pipe section 11 which extends at its lower end through an opening 12 in the top of a pit or well 13 located in the ground, as for example alongside of a railway track. The lower end of the pipe 11 connects with a water-supply pipe 14 which would lead to any suitable source of water supply, with valve mechanism represented at 15 interposed between the pipes 11 and 14 for controlling the supply of water to the 75 crane. The particular form of valve mechanism shown forms no part of my present invention but is of a construction commonly employed, and need not therefore be described, it being sufficient for the 80 present purpose, to state that this valve mechanism is operated to open the passage from the pipe 14 to the pipe 11, by lifting the rod represented at 16 which extends upwardly through the supporting base 10 and 85 is connected with an operating lever as hereinafter described.

The upper end of the pipe section 11 is surmounted by a frame 17 rigidly connected therewith and having its side wall cut 90 away as represented at 18 to provide at opposite sides thereof the curved surfaces 19 at opposite sides of the frame and the recess 20 at the side thereof extending at an angle to the last-referred-to sides, with 95 the edges of the frame adjacent the recess 20 upwardly converging as represented at 21 for a purpose hereinafter stated.

The upright water-conducting portion of the crane is formed of the tubular section 11 and the tubular section 22 extending above the section 11, these two sections being telescoped, with the section 22 movable up and down in the section 11, the section 22 being formed at its upper end with 100 a laterally-extending spout section 23 terminating in a downwardly-directed discharge portion 24. The joint between the 105

sections 11 and 22 is shown as packed, the packing being represented at 25 and located within an annular packing housing 26 provided at the upper end of the section 11, 5 the housing as shown comprising a sectional ring 27 surrounding the pipe 22 and secured to the upper internally expanded portion of the pipe 11.

The upper vertically-movable section of 10 the water-conducting portion of the crane, is supported from the frame 17 by means of a weight 28 secured to one end of the chain 29 which passes over a pulley 30 fixed on a shaft 31 secured in plate-sections 32 rising from the upper end of the frame 17, the other end of this chain being connected, through the medium of the connection shown at 33, with the pipe section 22 at a point concentric with the axis of this pipe 15 section. The connecting means 33 are shown as formed of a housing 34 to the upper portion of which the chain 29 is centrally connected, this housing containing a disc which is rotatable in the housing 34 and between which and the bottom of the housing ball bearings 36 are confined, the disc 35 resting upon these balls and affording means whereby the pipe 22 with its 20 spout 23 may be rotated in the pipe 11, without twisting the chain 29. The weight 28, which is preferably guided at a lug 37 thereon in a vertical guide slot 38 in the frame 17, is preferably of such weight that it will overcome the weight of the pipe section 22 and its spout 23, whereby the normal 25 position of these parts will be that illustrated in Figs. 1 and 3 and will require the forcing down of these parts to effect the lowering of the spout section, and means illustrated comprising a gear 39 fixed on a shaft 40 journaled at its ends in the members 32, the gear 39 meshing with a pinion 41 fixed on a shaft 42 journaled in one of the members 32, and meshing with a pinion 43 fixed on the end of the shaft 31. The shaft 40 is provided with an operating lever 44 which is shown as connected with one end of a cable 45, the opposite end being connected with a lug 46 provided on the outer end of the spout section 40 whereby the cable 45 is within easy reach of one standing on the tender to be filled. When the cable 45 is drawn upon to rock the lever 44 to the right in Fig. 4, it effects 45 the rotation of the pulley 30 in clockwise direction in Fig. 4 with the result of raising the weight 28 and permitting the pipe section 22, with its spout section 23, to lower in the pipe section 11, as for example to the dotted position represented in Fig. 3, thereby affording means whereby the discharge spout may be adjusted to the desired elevation for filling a tender.

At this point it may be stated that the 60 operator before lowering the spout section

as stated, would swing the latter from the position represented in Figs. 1 and 3 wherein the spout section 23 parallels the track, to a position at substantially right angles thereto, as represented at either of the 70 dotted positions in Fig. 2, depending upon which track at opposite sides of the stand-pipe the tender to be filled is located, in order that the discharge portion 24 of the 75 spout may be positioned over the filling opening in the tender. In this operation the operator would force the pipe section 22 with its spout section 23 downwardly, by operating the lowering mechanism described, sufficiently far to disengage the 80 spout section 23 from the recess 20, and after the spout section is positioned to extend crosswise of the track, would thereupon further lower the section 22 and the spout 23 to cause the discharge portion of 85 the spout to extend in the filling opening of the tank. Upon completing the filling of the tender the operator releases his grasp on the cable 45 and swings the spout section 23 back to a position in which it parallels the track, the counterweight 28 raising the movable parts to the normal position represented in Figs. 1 and 4, the inclined surfaces 21 being provided for insuring the return of the spout section 23 90 into the recess 20 which serves to hold the spout section 23, against accidental displacement, parallel with the track and out of the way of trains passing along the latter.

After the spout section 23 has been 100 moved to tender-filling position as hereinbefore explained, the operator opens the valve mechanism 15 to permit the water to flow from the pipe 14 through the crane and into the tender, this being effected by 105 forcing the valve rod 16 downwardly as by the means illustrated and comprising an arm 47 journaled on the shaft 40 and provided with an upwardly-extending operating lever 48 connected with a cable 49 also 110 connected with the lug 46 to extend into a position accessible to the operator, the valve mechanism 15 automatically returning to closed position when the operator releases his grasp on the cable 49.

The construction illustrated in Figs. 5 and 6 is like that of the preceding figures, except that the portion of the construction upon which the spout-depressing mechanism and the valve-operating mechanism, is located, instead of being fixed and the spout section swinging relative thereto, is so related to the spout section that these parts rotate as a unit about a base member represented at 50. In this construction the portion of the structure which directly carries the mechanism just referred to, is represented at 51 and is shown as formed of four 120 vertically-extending rods 52 disposed in a rectangular arrangement as shown in Fig.

6 and mounted in a disc 53 having annular concentric flanges 54 and 55, the disc 53 being supported, to be rotatable, on the base member 50 at ball bearings represented at 56 located between the flanges 54 and 55, the flange 54 overlapping the circular wall of the base member 50 and the flange 55 extending through a central opening 57 in the top of the base. In this construction the 10 upper telescoping section 22 of the crane is shown as surrounding the lower pipe section 11, and to insure the desired stability of the pipe section 22 and spout section 23, the pipe section 22 in this construction being 15 of relatively great length, I prefer to equip the pipe section 22 with rollers 58 which rollingly engage the adjacent ones of the rods 52 as shown in the drawings.

Inasmuch as the parts which support the 20 valve-operating mechanism are rotatable with the spout section, and the valve mechanism located in the well 13 for controlling the flow of water through the crane, is stationarily positioned, the valve-operating 25 rod 16, which extends through the disc 53 and through a segmental slot 59 in the top of the base 50, is so connected with the valve mechanism (not shown) which is operated through the medium of the rods 60 30 and may be of any suitable construction, that the valve rod 16 may bodily swing about the pipe section 11 in the swinging movement of the spout 23 and at all times maintain the desired operative connection 35 with the valve mechanism referred to, this being effected in the arrangement shown by interposing between one of the rods 60 and the rod 16 a plural ring construction involving a pair of rings one of which, represented at 61, is mounted on the pipe section to slide up and down thereon and be 40 rotatable thereon, and is connected with the rod 16, and the other of which rings (not shown) also surrounds the pipe section 11 45 and is adapted to slide up and down thereon and is interlocked with the ring 61 and connected with one of the rods 60, the latter extending through a slot (not shown) in the ring 61, this plural ring construction 50 being the same as that shown in Fig. 8, and hereinafter referred to.

The construction shown in Figs. 7, 8 and 9 involves the provision of a vertical pipe section 63 extending upwardly through a base member 64 on the top of the well 13, the pipe section 63 being mounted for turning, on a valve housing 65 which is located in the well 13 and is supported at the bottom thereof, this valve housing, with its valve mechanism (not shown) being of any suitable construction and communicating with a water-supply pipe, corresponding to the pipe 14. The particular bearing connection between the pipe section 63 and the housing 65, in accordance with the showing in the

figures now being described, involves a packed ball bearing joint as represented at 66.

It may be here stated that in this particular construction the telescoping feature, 70 which forms the gist of my invention is incorporated in a structure wherein not only is the pipe section 63 rotatable, but all the parts connected therewith above the bearing 66 rotate with this pipe section. The 75 upper telescoping section of the crane is represented at 67, and its spout portion, corresponding to the spout portion 23, being represented at 68, there being provided between the section 63 and 67 packing 69 as 80 in the construction shown in Fig. 3, permitting the section 67 to be raised and lowered in the section 63, but preventing leakage of water through the joint. The section 63 is surmounted by a frame 70 formed at its 85 upper end with a lateral extension 71 slotted as indicated at 72, the under side of the extension 71 at opposite sides of the slot 72 and represented at 73 forming guides for rollers hereinafter referred to, these portions of the extensions being provided with upwardly-extending ribs 74 through which a bolt 75 passes for insuring rigidity of the frame 70. The vertically-movable section 67 is pivotally connected as indicated 90 at 76 with the lower end of a link 77, the upper end of which is pivotally connected with a cross rod 78, to the opposite ends of which latter, the upper ends of links 79 95 are pivoted, the lower ends of the links 79 100 being connected together by a cross rod 80 carrying the rollers, hereinbefore mentioned, and represented at 81, these rollers being arranged directly beneath the surfaces 73 which latter form a track for the rollers. 105 The links 79 are connected as indicated at 79^a, through the medium of a chain 82 passing over a pulley 83 on a shaft 84 mounted in the upper end of the frame 70, with a counterweight 85 which is of such 110 weight as to return the pipe section 67 and spout section 68, together with the operating lever 77 and 79, to normal position after actuation as hereinafter described.

This construction is designed to be rotated 115 from the position in which the spout section 68 extends parallel with the track, into a position in which it is directly above a tender to be filled, by an operator standing on the ground, and to this end the pipe section 63 is shown as formed with a collar 86 extending above the base member 64 and equipped with a handle 87 by means of which the pipe section 63 and the parts supported thereby may be rotated into the desired position. The depressing of the pipe section 67, together with its spout section 68, to properly position the discharge end of the spout 68 relative to the filling opening of a tender, is effected by the operator draw- 120 125 130

ing to the right in Fig. 7 upon a cable 88 which is connected with the cross bar 80 and which when drawn upon operates against the action of the weight 85, to shift the lower end of the links 79 to the right in Fig. 7, and by reason of the vertical guidance of the pipe section 67 in the pipe 63, force the link 77, and therefore the pipe section 67 and spout 68, downwardly, throughout a distance depending upon the extent of movement of the link 79 by the operator drawing on the cable 88.

In this construction the valve-operating rod represented at 89 and shown as connected at its upper end with an arm 90 rigid on the shaft 84 and adapted to be rotated therewith, extends downwardly through the base member 64 and serves, as through the medium of the plural ring coupling represented at 91 and of a construction such as that described and represented in Fig. 5, to operate the valve mechanism (not shown) hereinbefore referred to for controlling the flow of water through the crane.

It will be understood from the foregoing that a structure constructed in accordance with my invention is not only comparatively simple and economical to build, but provides for the proper positioning of the spout section relative to the filling opening of a tender regardless of the height at which the tender extends, thereby adapting the water crane for universal use at railway tracks. Furthermore, and as a feature of special advantage, the height to which the water must be forced in the vertical water-conducting portion of the crane, is dependent on the height of the tender to be filled, as distinguished from a structure wherein the vertical portion of the crane is of fixed height and the water must be forced to the same height, for delivery to the tender, regardless of the height of the tender. Thus it is only necessary to force the water to the greatest height when the spout is at the greatest elevation it assumes when filling the highest tenders, and thereby a great saving is effected.

While I have illustrated and described certain particular constructions in which my invention is embodied, I do not wish to be understood as intending to limit it thereto as the same may be variously modified and altered and the invention embodied in other structures, without departing from the spirit of my invention.

What I claim as new and desire to secure by Letters Patent is:

1. A water-crane formed with an upright water-conducting portion formed of lengthwise telescoping sections, counterbalancing means for said upper section constructed and arranged to raise said upper section upon releasing the latter after depressing it, and

mechanism, involving relatively movable parts, for forcing said upper section downwardly against the resistance of said counterbalancing means.

2. A water-crane formed with an upright water-conducting portion formed of lengthwise telescoping sections, the upper one of said sections being rotatable on the lower one of said sections, a support arranged to rotate with the upper one of said sections, and mechanism, on said support through the medium of which the said upper section may be caused to extend at different elevations.

3. A water-crane formed with an upright water-conducting portion formed of lengthwise telescoping sections, the upper one of said sections being rotatable on the lower one of said sections, valve means controlling the flow of water through the crane, said upper section being rotatable relative to the lower section in the closed position of said valve means, a support arranged to rotate with the upper one of said sections, and means on said support through the medium of which the said upper section may be caused to extend at different elevations.

4. A water-crane formed with an upright water-conducting portion formed of lengthwise telescoping sections, the upper one of said sections being rotatable on the lower one of said sections and surrounding said lower section, a support arranged to rotate with the upper one of said sections, and mechanism on said support through the medium of which the said upper section may be caused to extend at different elevations.

5. A water-crane formed with an upright water-conducting portion formed of lengthwise telescoping sections, the upper one of said sections being rotatable on the lower one of said sections, a support arranged to rotate with the upper one of said sections, and counterbalancing means on said support, for said upper section.

6. A water-crane formed with an upwardly extending water-conducting portion formed of lengthwise telescoping sections, the upper one of said sections being rotatable on the lower one of said sections, a support arranged to rotate with the upper one of said sections and relative to which said upper section is movable up and down, a cable connected with the upper one of said sections and extending over said support, and means engaging said cable and operating to exert a lifting action on the upper one of said sections.

7. A water-crane formed with an upwardly extending water-conducting portion formed of lengthwise telescoping sections, a support relative to which the upper one of said sections is movable up and down, a cable connected with the upper one of said sections and extending over said support, means engaging said cable and operating to exert

- a lifting action on the upper one of said sections, and means on said support for sliding said upper section relative to said lower section.
5. 8. A water-crane formed with an upright water-conducting portion formed of lengthwise telescoping sections, the upper one of said sections being rotatable on the lower one of said sections, a support arranged to 10 rotate with the upper one of said sections, counterbalancing means on said support, for said upper section, and means on said support for sliding said upper section relative to said lower section.
15. 9. A water-crane formed with an upright water-conducting portion formed of lengthwise telescoping sections, the upper one of said sections being rotatable on the lower one of said sections, a support arranged to 20 rotate with the upper one of said sections and in which the latter is movable up and down, and means on said support through the medium of which the said upper section may be caused to extend at different elevations.
25. 10. A water-crane formed with an upright water-conducting portion formed of lengthwise telescoping sections, and means controlling the elevation of said upper section comprising a support, counterweight 30 means engaging said support and the upper one of said sections, and gear mechanism operating, when actuated, to relieve said upper section of the weight imposed by said counterbalancing means.
35. 11. A water-crane formed with an upright water-conducting portion formed of lengthwise telescoping sections, a supporting member extending to a point above the upper one of said sections and relative to which said upper section is movable, valve mechanism controlling the flow of water through said portion, and valve-operating mechanism carried by said supporting member.
40. 12. A water-crane formed with an upwardly extending water-conducting portion formed of lengthwise telescoping sections, the upper one of which is rotatable relative to the lower section, a supporting member 45 rotatable with said upper section, said upper section being movable up and down relative to said supporting member, valve mechanism controlling the flow of water through said portion, and valve operating mechanism carried by said supporting member.

BARTON S. SNOW.
